FIREPLACE

Esther Worth Fogerty, Clinton Gordon Fogerty,
and Clifford Worth Fogerty, Hialeah, Fla.

Application October 17, 1936, Serial No. 106,170

2 Claims. (Cl. 126—120)

An object of the invention is to provide a fireplace construction in which the parts are so shaped and arranged that the heat produced by the fuel is effectively reflected and radiated into the room to be heated.

A further object is to provide a fireplace made of a very few component parts and wherein these parts may be preformed at a factory and easily fitted together at the place of installation without the services of a skilled mason.

A still further object is to provide a fireplace with a rear portion which is curved upwards towards the chimney to cause the smoke and burned gases to be rapidly transferred to the chimney and be kept from getting out into the room. This rear portion at the same time is highly heated by the ascending gases and flame and thereupon reflects and radiates the heat into the room.

A still further object is to provide a fireplace which may be made and assembled with a minimum amount of labor and cost. Still other objects will become apparent to those skilled in the art as the description thereof proceeds. For a better understanding of the invention, however, reference is made to the accompanying drawing, in which;

Fig. 1 is an end view of a fireplace structure embodying the invention,

Fig. 2 is a front view of the fireplace of Fig. 1,

Fig. 3 is a partial section through the line 3—3 of Fig. 1 looking in the direction of the arrow,

Fig. 4 is a top view of the hearth or base plate,

Fig. 5 is a top view of the hood and,

Fig. 6 is a top view of a preferred form of damper.

Referring to Figs. 1, 2 and 4, the fireplace comprises a flat base plate or hearth piece 3 on which the fire is built, this having a groove 4 extending along two sides and across the back. In this groove is fitted or seated the two cheek or side members 1 and a curved rear or heat deflecting member 2 which is concave towards the front as shown. The upper edges of the side pieces 1 are formed with rabbets 5 which project into grooves 5' formed in the rear member 2 whereby the rear member ties the two side members together. As shown in Fig. 3 a fireproof cement 19 may be applied to the joints to firmly bind the several members in place. A notch or recess 20 is formed near the top of the members 1 and a front support or tie member 9 placed in these notches extends between members 1 and ties them together to further support them. In the opening formed between members 2 and 9 is placed the damper or draft regulator 6 whose journal pins 8 are seated

in notches 7 formed in the side pieces 1. A chain 16 is attached to the damper near one edge and a hook 21 near its end may be looped over a pin 17 seated in the side piece 1 to retain the damper in open position.

Surmounting the above mentioned parts is a hood 11 which is hollow and has upwardly sloping side portions 13 and 15 and front portion 14 terminating in a top flat area or portion 12 in which is the hole or opening 19 through which the burned gases and products of combustion pass to the usual chimney, the latter not being shown and forming no part of our invention. For the purpose of removing the ashes formed, a hole 22 is formed through the base near its center and through which the ashes may be passed. A removable door or cap 10 is fitted to cover this opening when not in use.

We prefer to form the several parts of the fireplace of soft clay or other known ceramic materials in separate molds, one mold being specially shaped for each piece. After removal from the molds, the parts are heated or burned in kilns or heating ovens until hard like brick or terra-cotta. If desired, and as shown in Fig. 6, iron or steel reinforcing rods 18 may be inserted while the clay is still soft and remain in the damper during the burning process, to further strengthen it. Similar reinforcing may be incorporated in any of the other molded parts, as desired. It will be understood that cement may be used at any or all of the joints to secure the several parts firmly in place.

It will thus be seen that each of the several parts of the fireplace may be molded to its proper size and shape and prepared at a factory so that the workman at the site has merely to assemble the several parts together at the site of installation. The surfaces of the parts may be left plain or they may be marked off to resemble bricks, the front surface of the rear member 2 and the upper surface of base member 3 which lies between the side members being shown so marked off in Figs. 2 and 4. When installing in the vicinity of wooden partitions or walls, the outer surfaces may be faced with cement, brick or similar material to further decrease the fire hazard. While we have shown the hood formed in a single piece, it may be formed in two similar pieces if desired with a rabbet joint along the center, such as the joint 5, 5' of Fig. 3.

While we have indicated and described one arrangement for carrying our invention into effect, it will be apparent to one skilled in the art that our invention is by no means limited

to the particular organization shown and described, but that many modifications may be employed without departing from the scope of our invention as set forth in the appended claims.

5 What we claim as novel and desire to secure by Letters Patent is:

1. A fireplace comprising the combination of a flat base, oppositely disposed parallel side pieces mounted on said base, the upper edge 10 of each of said side pieces being curved and having a thin, projecting rabbet; a concavely formed rear piece provided with spaced apart parallel grooves, said projecting rabbets being coated with cement and being seated in said 15 respective grooves; a support spaced from said rear piece and having its ends secured to the upper portions of said side pieces and a hollow hood having a flat base engaging the upper ends of said side pieces and said rear piece, the rear 20 wall of said hood being vertical and the side and front walls thereof converging upwardly into a flat top portion adapted to support a chimney.

2. A fireplace comprising the combination of a rectangular shaped base portion having a 25 groove formed parallel to three edges thereof,

a concavely curved heat deflecting portion having its lower edge seated in the center portion of said groove, vertically disposed side walls having their lower edges seated in the respective side portions of said groove and the rear portion of their upper edges in engagement with the concave surface of said heat deflecting portion and the front portion of their upper edges being flat and in the same plane as the upper edge of said curved heat deflecting portion and 5 a hollow hood having a flat base, upwardly converging side walls, a vertical rear wall and a rearwardly inclined front wall, the distance between said front and rear walls being substantially greater than the length of the flat upper 10 edges of the side walls, the lower surfaces of the side walls of said hood being in engagement with the flat upper edges of said first named side walls and the lower surface of the rear edge of the hood being in engagement with the upper 15 edge of said heat deflecting portion.
